Primary Examiner — Cynthia Ramirez*Assistant Examiner* — Michael A Maharajh(74) *Attorney, Agent, or Firm* — Downs Rachlin Martin PLLC(57) **CLAIM**

The ornamental design for a training ball, as shown and described.

DESCRIPTION

FIG. 1 is a first side view of a training ball showing my new design;

FIG. 2 is a right side view thereof;

FIG. 3 is a third side view thereof;

FIG. 4 is a left side view thereof;

FIG. 5 is an end view thereof; and,

FIG. 6 is a second end view thereof.

The broken lines in the Figures are for the purpose of illustrating unclaimed portions of the training ball and form no part of the claimed design.

1 Claim, 6 Drawing Sheets(56)
